UNITED STATES PATENT OFFICE.

JAMES HENRY WINSLOW, OF LYNN, MASSACHUSETTS.

IMPROVEMENT IN PRESERVE-CAN HOLDERS.

Specification forming part of Letters Patent No. **158,161**, dated December 22, 1874; application filed November 30, 1874.

To all whom it may concern:

Be it known that I, JAMES H. WINSLOW, of Lynn, in the county of Essex and State of Massachusetts, have invented a new and Improved Preserve-Can Holder, of which the following is a specification:

My invention consists of a pair of rubber-lined clamping-jaws, with the contrivance for opening and closing them and holding them closed; also, with clamp-screws or other contrivance for detachably connecting the clamping-jaws to a table or other support, all contrived and adapted for holding glass fruit-jars while screwing the covers on or off, the said holder being contrived so as to hold jars of different sizes.

Figure 1 is a plan view of a jar-holder of my invention, with some parts represented in horizontal section. Fig. 2 is a transverse section taken on the line *x x* of Fig. 1; and Fig. 3 is a plan view of a holder with a different contrivance of the operating and holding apparatus.

Similar letters of reference indicate corresponding parts.

A and B represent a pair of curved clamping-jaws, pivoted together at one end, C, and rubber-lined on the inside D. One of said jaws has a clamp, E, at each end by which to fasten it to the edge of the table readily, and the other has a toothed segment, F, with which a worm, G, having a hand-crank for turning it, gears to turn it for opening and closing the jaws.

Instead of the worm, a wheel, I, with a le-

ver, J, may be used for working the movable jaw, and a ratchet-bar, K, and a catch-pawl, L, may be used for holding it when closed on the jar.

Any approved means of working and holding the movable jaw may be used, and I do not, therefore, limit myself, in this respect, to any particular contrivance.

The jaws are faced on the side which clamps against the bottle with rubber, or it may be any flexible substance, although rubber is the best for the glass to bed in, so as to hold firmly without breaking, and, if found best, the surfaces pressing against the glass may be corrugated or otherwise roughened.

The jars are set in the space between the jaws, and they are forced up tight against the jars, which are thereby held much firmer than they can be by hand, with much less labor, and by one person, whereas it requires two—one to hold the jar and the other to turn the cap—when done by hand.

Having thus described my invention, I claim as new and desire to secure by Letters Patent—

The combination of the curved clamping-jaws A B, pivoted together at C, and elastic facing material D, when provided with attaching-clamps E and operating and holding apparatus, substantially as specified.

JAMES H. WINSLOW.
